DOUBLE TUBE TROCAR DEVICE

Harm Harms, Benld, Ill.

Application December 22, 1948, Serial No. 66,789

1 Claim. (Cl. 27—24)

1

My invention relates to an improvement in trocars. A trocar is an instrument used by the undertaking profession in preparing a corpse for the process of embalming. The instrument is used to pierce the walls of the body and enter the abdominal or respiratory cavities of the body and then by suction extract or remove as nearly as possible, any and all liquids, blood or aqueous matter or material from the body.

The trocars now commonly used consist of a tubular element having a sharp point on one end thereof, a handle on the other end, holes in the point end of the tube, and having a hose connection to the handle end of the tube. In using the trocar a suction is produced in the trocar through the hose by any suitable means, such as a pump, a water pressure siphon jet or the like. In the process of using the trocar the wall of the body is pierced by the sharp point of the trocar and the tube of the trocar then advanced into the desired body cavity, whereupon the suction being produced in the trocar tube will pull any liquid, blood or aqueous matter surrounding the trocar tube through the holes therein into the tube and to and through the discharge end of the hose to dispose of the material being drawn into the trocar.

The difficulty in using the above described trocar is that the liquids, blood and aqueous material in the body is being drawn therefrom under the impetus or force of suction, which is a positive force. The result of this force is that tissues of the body, fat, congealed blood or blood clots and the like are drawn around the trocar tube and across the holes therein and close or clog the holes in the trocar tube and therefore the process of removing the liquid, blood and aqueous matter from the body is stopped until the trocar is again opened up or unclogged to again permit the free passage of material through the trocar.

In view of the foregoing described trouble and difficulties I have provided my improved trocar in which the liquids, blood and aqueous matter to be removed from the body drains by gravity into the trocar tube and is then removed therefrom by suction, and as the material that has drained into the trocar tube has been removed therefrom, air from outside the body is permitted to enter the trocar and pass through the suction tube of the trocar to prevent suction on the materials in the body whereby they may be drawn into the trocar tube openings to close or clog them as above described. This and other objects of my invention will be more detailed and fully explained as this description progresses.

2

Now referring to the accompanying drawings in which similar numerals of reference designate the same parts throughout the several figures of the drawings; Fig. 1 is a side view of my improved trocar.

Fig. 2 is a longitudinal detail sectional view of my improved trocar.

Fig. 3 is a transverse sectional view of my improved trocar, the view being as seen from the line III—III in Fig. 1 and looking in the direction of the arrows.

Fig. 4 is a transverse detail sectional view of my improved trocar, the view being as seen from the line IV—IV in Fig. 1 and looking in the direction of the arrows.

Fig. 5 is a head end view of a round end closure element for the trocar tube.

Fig. 6 is a side view of the trocar tube closure element shown in Fig. 5.

Fig. 7 is a side view of a piercing tip that may be placed on one end of the trocar tube.

Fig. 8 is an end view of the piercing tip, the view being as seen from the left of Fig. 7.

Fig. 9 is a detail side view of one end of the trocar tube and showing the piercing tip of Fig. 1 being replaced by the round nosed closure element shown in Figures 5 and 6.

Fig. 10 is a longitudinal detail sectional view of the trocar end structure shown in Fig. 9.

In the drawings my improved trocar device is shown as having a hollow handle 15 in which there are holes 16 to permit the passage of air in or out of the handle cavity C.

The front end of the handle 15 is provided with a fitting F, one end of which is threaded as at 17 and is threaded into the front end of the handle element 15. The fitting F is provided with a hexagonal shoulder portion 18 that bears against the outer surface of the front end of the handle 15 and by which the fitting 15 may be turned to tightly screw the threaded end of the fitting F into the handle element 15. The fitting is also provided with a forwardly extending nipple portion 19. The fitting F is provided with an axial bore 20 therethrough and in which is tightly pressed the rear end of a trocar tube 21 which opens into the handle cavity C. The forward end of the trocar tube 21 is provided with a plurality of holes or perforations 22 therethrough that are in staggered positions around the forward end portion of the tube 21. The inner surface of the forward end portion of the tube 21 is threaded as at 23 to receive a closure element or tip for the end of the trocar tube.

As shown in Figures 1 and 2, the trocar tube

3

21 is provided with a piercing tip T that has a threaded stud portion 24 that projects rearwardly from a cylindrical portion 25 that is larger in diameter than the stud 24 and is the same diameter as the outside diameter of the trocar tube.

The forward portion of the tip T is made in a rather long four sided pyramid tapering fashion 26 and terminating in a sharp point 27. The pyramid formation 26 is probably the preferable formation, however the formation 26 might be three, five or more sided or even conical in shape and still work satisfactorily. The threaded stud 24 is receivable in the threads 23 in the inner forward end of the trocar tube 21 and the shoulder 28 formed between the stud 24 and cylindrical portion 25 of the tip T will bear against the forward end of the trocar tube 21 to provide an even, smooth and solid mounting of the tip T on the forward end of the trocar tube 21.

In Figures 5 and 6 is shown a substantially hemispherical shaped tip 29 that has a threaded stud 24a that is a duplicate of the stud 24 of the tip T and is receivable in the threaded forward end of the trocar tube 21 the same as is the stud 24 of the tip T. The diameter of the tip head 29 is the same as that of the outside of the trocar tube 21 and the tip shoulder 28a is the same as the tip shoulder 28 of the tip T and serves the same purpose. The two tips T and 29 are interchangeable for purposes that will later be explained.

The trocar tube 21 is provided with at least three indentures 30 that are positioned immediately in the rear of the holes or perforations 22 in the trocar tube 21 and are spaced 120 degrees apart around the trocar tube 21. The indented portions 30 of the trocar tube present inwardly directed support protrusions 31 in the trocar tube 21 for the support and positioning of a suction tube in the trocar tube 21 as will later be described.

The trocar device is provided with a suction tube 32 whose outside diameter is substantially less than the inside diameter of the trocar tube 21. The suction tube 32 is axially positioned in the trocar tube 21 and handle 16. The outside surface of the forward end of the suction tube 32 is spaced away from the inner surface of the trocar tube 21 and is held in its above mentioned axial position in the trocar tube 21 by the protrusions 31 of the trocar tube 21. The forward end 32a of the suction tube 32 is spaced a short distance away from the rear end of the stud 24 or 24a, as the case may be, so as to leave several, four or six of the holes or perforations 22 in the trocar tube 21 between the rear end of the stud 24 or 24a and the forward end 32a of the suction tube 32. The remaining holes or perforations 22 in the trocar tube 21 are grouped or positioned around the forward end portion of the suction tube 32. The rear end portion of the suction tube 32 is tightly pressed through a nipple fitting 33 that is threaded through the rear end wall 15a of the handle element 15 and a lock nut 34 is threaded on the nipple 33 and bears against the rear end wall 15a of the handle element 15 to lock in adjusted longitudinal positions in the handle element 15.

The rear end of the suction tube 32 projects rearwardly from the rear end of the nipple 33 and one end of a flexible suction hose 35 is slipped thereon. The other end of the suction hose 35 is connected to any suitable suction producing device such as a pump or standard water siphon jet device or the like, not shown.

4

To use the trocar device the piercing tip T is first placed on the forward end of the trocar tube 21 as shown in Figures 1 and 2, whereupon the handle 15 may be held in one's hand ready for use. The trocar device is then held with the tip point 27 against the surface of the body of the corpse and then the device is pressed to cause the point 27 to pierce the wall of the body and enter into the abdominal or chest cavity of the body, as the case may be. This having been done, the device may then be removed from the body and the tip T removed from the trocar tube and replaced by the blunt or round nosed tip 29 as shown in Figures 9 and 10, whereupon the trocar tube may be reinserted into the body cavity through the opening or hole previously made therein by the sharp pointed tip T. The trocar tube 21 now having the blunt tip 29 may be inserted into the body cavity and moved around to any desired depth and part of the cavity. This having been done the liquids, blood or aqueous material contained in the cavity will drain, by gravity, through the holes or perforations 22 in the trocar tube 21 into the trocar tube 21 and submerge the end portion 32a of the suction tube 32 and even fill some of the forward portion of the trocar tube 21. Now due to suction created in the suction tube 32 by the afore mentioned suction devices the material that has drained into the trocar tube 21 will be sucked and removed therefrom through the suction tube 32 and hose 35 to any suitable place of disposal.

If the material in the trocar tube 21 is removed through the suction tube 32 faster than it will drain in through the holes or perforations 22 in the trocar tube and the level of the material in the trocar tube falls below the forward end 32a of the suction tube 32 then air will be drawn in through the holes 16 in the handle 15 and pass through the handle cavity C and through the trocar tube 21 to and through the forward end of the suction tube 32 and thence on through the suction tube 32 and hose 35 to the point of discharge or disposal and no suction or vacuum tendencies will have been produced within the cavity of the body being emptied, therefore no materials of a solid nature or tissues of the body will be drawn or packed around the trocar tube 21 that will clog or stop up the drainage holes or perforations 22 in the trocar tube 21.

Due to the construction of the device and its use as above described it is obvious that the materials removed from the body cavity are only removed as fast as they will drain into the trocar tube 21 and there is nothing to force the drainage, therefore the instrument will always remain open for the free and easy passage of the materials being passed therethrough. This is in conspicuous contrast to the trocar devices now in common use which do readily clog and stop up and have to be removed from the body and cleaned out and then reinserted a considerable number of times before the job is completed. In view of this trouble it becomes obvious that my improved trocar device is much more efficient and faster in its work than those now in use.

If for any reason it does become necessary, as the operator of the device does want to use suction force, it is only necessary for him to place his fingers over the holes 16 to close them against the passage of air therethrough and the full amount of suction may be received as the suction devices will produce.

75 While my improved trocar device as shown

and herein described is probably the preferred form of the device it is to be understood that such modifications and variations of the device may be employed as lie within the scope of the appended claim without departing from the spirit and intention of the invention. Now having fully shown and described my invention, what I claim is:

A trocar device comprising the combination of a hollow handle element, a trocar tube, and a suction tube, one end of said trocar tube being rigidly attached to one end of said handle and opening into the hollow thereof, the other end of said trocar tube being closed, said suction tube being positioned within and spaced away from the inner surface of the trocar tube and extending through the hollow of the handle to and through the other end of the said handle and being tightly connected thereto to position and hold each tube and the handle in axial alignment, each with the other, one end of said suction tube being open and being positioned close to the closed end of the trocar tube, said trocar tube having perforations in its side walls ad-

jacent the closed end, said perforations extending partly in front and partly behind the open end of the suction tube, said handle element having an opening therein that is openable and closable by the finger of the operator of the trocar device for the purpose described.
